UNITED STATES PATENT OFFICE.

WILLIAM J. CLARK, OF DETROIT, MICHIGAN.

NECKTIE.

1,295,696.

Specification of Letters Patent. Patented Feb. 25, 1919.

Application filed November 29, 1918. Serial No. 264,587.

To all whom it may concern:

Be it known that I, WILLIAM J. CLARK, citizen of the United States, residing at Detroit, county of Wayne, State of Michigan, 5 have invented a certain new and useful Improvement in Neckties, and declare the following to be a full, clear, and exact description of the same, such as will enable others skilled in the art to which it pertains to 10 make and use the same, reference being had to the accompanying drawings, which form a part of this specification.

My invention relates to neckties of the "four-in-hand" type shown in the accompanying drawings and more particularly pointed out in the following specification and claims.

It is well known that ties of this character are usually constructed with a loose padding of canton flannel or like material inclosed within its folds to give the latter the desired "fullness" when worn, and that after the tie has been used it soon becomes creased and the padding "bunched" within its folds, 25 making it difficult to smooth and press. Attempts have been made to overcome this objection by sewing the padding to the edges of the tie proper, but this necessitates a greatly increased cost of production and 30 makes it necessary to press both the tie and padding together and as one or the other usually shrinks "a rope-like" effect is often produced which is impossible to overcome by pressing.

The object of the present invention therefore is to overcome these and other objections by constructing a tie adapted to be opened throughout that portion of its length in which the "knot" occurs when tied;—the 40 padding adjacent to the "open portion" being permanently secured at one end only by a line of transverse stitching,—the other end of the padding being detachably secured by an engaging device having one member attached to the padding, and the other member to the continuation of the padding at the opposite end of the "open portion"; or if preferred to the neck band of the tie proper.

With the foregoing and other objects in view, the invention resides in the combination and arrangement of parts, and in the details of construction hereafter described and claimed, it being understood that 55 changes may be made in the precise embodi-

ment herein disclosed without departing from the spirit of the invention.

In the accompanying drawings forming part of this specification:—

Figure 1 is an elevation of a four-in-hand tie viewed from the back, with a portion of its length opened and a section of the padding "released" for pressing. 60

Fig. 2 is a rear elevation of the tie shown in the preceding figure, the "open section" 65 being closed and secured as it would appear when ready for wear.

Referring now to the letters of reference placed upon the drawings:—

A, denotes a four-in-hand tie of usual 70 shape, provided with an "open section" at the back in its enlarged portion which includes that portion forming the "knot" when worn. B, B are flaps formed of the same material as the body of the tie, the edges of 75 which are provided with detachable fastening devices C, that they may be secured together to close the "open section".

D, indicates a lining or padding of canton flannel or other suitable material, permanently secured to the tie proper by a line of transverse stitches E, extending across the adjacent edges of the tie at the back below the "open section". F, denotes a detachable fastening device adapted to secure 85 the free end of the lining to the adjoining end of the lining secured within the narrow portion of the tie.

G, is a flap preferably formed of the same material as the body of the tie which 90 serves to cover the adjoining ends of the lining:—the flap itself being partially covered by the parts B B when closed for wear.

It is well understood that the portion of 95 the tie which becomes crumpled through use is that part of the tie in which the "knot" occurs when worn.

By providing a portion of the tie which may be opened to include that part forming 100 the "knot" both the tie and its padding may be pressed to overcome the wrinkles. So also by permanently securing the lining to the tie at one end only and detachably securing it at the other, each part may be 105 independently pressed without danger of the parts being misplaced:—furthermore as the lining may be detached at one end there is no tendency to "draw" due to shrinkage or other cause, and should it shrink it may be 110

easily stretched to its initial length and thus engaged to the adjoining end of the lining by the detachable fastening device, as before.

Having thus described my invention, what

5 I claim is:

1. A tie of the character described folded longitudinally having a section intermediate of its length adapted to "open" at the back to expose a lining, an inner divided lining secured to the body of the tie by a line of stitches extending transversely across the folds at the back of the tie, a detachable fastening device for securing the free end of the lining to its adjoining end, and means 10 for detachably securing together the edges of the "open section" at the back of the tie.
2. A tie of the character described folded longitudinally with the edges of the folded portion sewed together but with an intermediate "open" section having overlapping edges adapted to be folded back to expose a lining, a divided lining lodged within the folds of the tie and permanently secured thereto adjacent to one end of the intermediate open section at the back of the tie, a 15 fastening device for detachably securing the

free end of the lining to its adjoining end, and means for detachably securing together the overlapping edges of the open section at the back of the tie. 30

3. A tie of the character described folded longitudinally with its edges secured together and having an intermediate overlapping portion adapted to open to expose a lining within, a divided lining housed within the folds of the tie secured thereto by a line of stitches extending transversely across the folds of the tie at the back adjacent to one edge of the intermediate open section, means for detachably securing the free end 35 of the lining to its adjoining end, means for detachably securing the edges of the folded portion of the back of the tie together, and a flap adapted to close over the adjoining ends of the lining. 40

45 In testimony whereof, I sign this specification in the presence of two witnesses.

WILLIAM J. CLARK.
